RICHARD W. RAFTIS, OF CHICAGO, ILLINOIS; LILLIAN B. RAFTIS, EXECUTRIX OF SAID
RICHARD W. RAFTIS, DECEASED, ASSIGNOR TO LILLIAN B. RAFTIS, OF CHICAGO,
ILLINOIS

WALL

Application filed December 28, 1928. Serial No. 328,897.

My invention relates to building construction and more specifically to an improved wall construction. It includes, among its objects and advantages, improved facility and reliability in the location of base boards and moldings.

In the accompanying drawing:

Figure 1 is a horizontal section through a portion of a wall according to the invention.

Fig. 2 is a similar section through the joint with a nailing block in a thicker wall.

Fig. 3 is a similar section through a joint provided with nailing blocks in a still thicker wall.

Fig. 4 is a side elevation of a portion of a wall according to the invention.

In the embodiment of the invention selected for illustration, the wall is made up of a plurality of courses of individual building units with horizontal mortar joints between each course and the courses above and below. Each course has vertical mortar joints between the individual units and the joints in successive courses are staggered. In the form illustrated in Fig. 4, the units are square in side elevation and the joints of each course are set half-way between the vertical planes of the joints of adjacent courses.

Each unit comprises a cellular body 10 having intermediate partitions 12. The units in the course level with a molding or base board have each one plain end 14 and a V-shaped notch 16 in the other end. They are laid in pairs with the V-shaped notches facing each other, as clearly indicated in Fig. 1, so that alternate joints are plain, as indicated at 18, and the remaining joints have square recesses to receive nailing blocks 20. These blocks can simply be dropped in place when the units are being put in position. The tile in the course below may be laid with the cells horizontal to provide a firm support for the nailing block 20, although this is not necessary as pushing the tile against each other and putting the mortar in place will furnish adequate support.

The notches are of such a size as to leave sufficient depth for a good mortar joint seal at 22 but preferably large enough so that the partitions defining the notches 16 inter-

sect the faces of the wall at or near the joint. Thus, the material at point 24 in Fig. 1 is effectively braced by the adjacent portions 26 and 28 defining the face of the unit and the side of the notch 16 respectively, and lying at an angle to each other. The main advantage of this feature is that the material at 24 is so well connected with the rest of the unit that breakage in handling is not a serious risk.

It will be noted that in the thicker wall shown in Fig. 2, I employ a slightly larger nailing block 30 so as to maintain the effective bracing of the edge of the unit at 32. It is not necessary to increase the size of the nailing block by an amount exactly equal to the increased thickness of the wall. Upon reference to Fig. 2, it will be noted that the mortar joint at 34 is somewhat deeper than that at 32.

For still thicker walls, as indicated in Fig. 3, I prefer to employ two nailing blocks 36 and 38, in which case the positioning of the blocks is determined by the best depth for the mortar joints at 40 and the best bracing for the edges of the units at 42.

It will be apparent that the horizontal and vertical mortar joints at 44 and 46 in Fig. 4 completely enclose and seal the nailing strips so that their faces are not accessible to a burning action in case of fire. To get any assistance from the nailing block in supporting combustion, it would be necessary to heat the entire wall to such a temperature that the more volatile constituents of the wood would be vaporized and force their way out through the mortar joints.

After the units are laid, the wall is completed in the usual way, as by positioning grounds 48 where the base board and moldings are to be mounted later. These grounds also function as a depth gage for the plasterer who applies the plaster 50 to the rest of the wall. Wherever plaster is to be applied to the faces of the units should be keyed. In the case of the inside wall or partition illustrated in Fig. 1, the units are keyed on both sides. The grounds 48 are fastened to the wall by driving one or more nails 52 through the ground and into each of the nail-

ing blocks. Thus, with a building unit one foot square, there will be a nailing every two feet to hold the ground in place.

After the plaster has been applied, the 5 grounds provide wood surfaces flush with the plaster, to which the base board and moldings may be attached.

Without further elaboration, the foregoing 10 will so fully explain the gist of my invention that others may, by applying current knowledge, readily adapt the same for use under various conditions of service.

I claim:

1. A wall comprising a plurality of courses 15 of cellular tiles with vertical mortar joints between the tiles in each course, and horizontal mortar joints between the courses, certain of said vertical joints being formed with recesses symmetrically located between opposite faces of the wall, said recesses being square in plan view with one diagonal parallel to the wall, and square nailing blocks filling said recesses and sealed in by the mortar of the adjacent joints, said blocks being accessible from both sides of the wall by nailing through the mortar, the tiles forming the recesses having each one vertical edge grooved and the other plain whereby the nailing blocks are located in alternate vertical joints 30 in a given course.

2. A wall comprising a plurality of units held in place by cementitious material at the joints, certain of said units having grooves in their vertical edges, said grooves having 35 faces forming a right angle, so that two of said units when placed end to end with their grooves facing each other form a square shaped recess adapted to house nailing blocks substantially square in cross section, and nailing blocks housed in said recesses and completely sealed up in the cementitious material.

3. A wall comprising building units and square nailing strips embedded in said wall, said units defining square cavities between 45 their adjacent edges to receive said strips, said units extending beyond said strips to define mortar spaces on both sides of said strips, and mortar filling said spaces, whereby said strips are completely sealed up and fireproofed.

In testimony whereof, I have signed my name to this specification.

RICHARD W. RAFTIS.
